(57) **CLAIM**

The ornamental design for a bird feeder, as shown and described.

DESCRIPTION

FIG. 1 is a front elevation view of a first embodiment of the bird feeder showing my new design, a back elevation view being substantially similar. All other sides of this first embodiment are essentially structurally the same as in the second embodiment, the only difference being that there is no inner central cord in the upper chamber;

FIG. 2 is a front elevation view of a second embodiment of the bird feeder showing my new design, a back elevation view being substantially similar;

FIG. 3 is a right elevation view of the bird feeder illustrated in FIG. 2, a left elevation view being substantially the same;

FIG. 4 is a front perspective view of the bird feeder illustrated in FIG. 2;

FIG. 5 is a front perspective view of the bird feeder illustrated in FIG. 2 viewed from below;

FIG. 6 is a right perspective view of the bird feeder illustrated in FIG. 2 viewed from below;

FIG. 7 is a top plan view of the bird feeder illustrated in FIG. 2; and,

FIG. 8 is a bottom plan view of the bird feeder illustrated in FIG. 2.

The portion of the looped-hanger in FIGS. 2 through 6 that is shown in broken lines shows the environment only, and forms no part of the claimed design.
